United States Patent Office

Des. 191,708
Patented Nov. 7, 1961

191,708

RADAR CONSOLE

Carl W. Sundberg, Bloomfield Hills, and Richard W. Figgins, Birmingham, Mich., assignors to Sperry Rand Corporation, a corporation of Delaware

Filed Dec. 24, 1959, Ser. No. 58,796

Term of patent 14 years

(Cl. D26—14)

FIG. 2.

FIG. 1.

FIG. 4.

FIG. 3.

FIG. 1 is a front elevational view of a radar console showing our new design;

FIG. 2 is a side elevational view taken from the right of FIG. 1;

FIG. 3 is a side elevational view taken from the left of FIG. 1; and

FIG. 4 is a rear elevational view.

We claim:

The ornamental design for a radar console, as shown.
